UNITED STATES PATENT OFFICE.

EDWARD L. TAFT, OF GARDNER, MASSACHUSETTS.

DESIGN FOR A WATER-CLOSET SEAT.

SPECIFICATION forming part of Design No. 30,285, dated February 28, 1899.

Application filed December 20, 1898. Serial No. 699,867. Term of patent 14 years.

To all whom it may concern:

Be it known that I, EDWARD L. TAFT, a citizen of the United States, residing at Gardner, in the county of Worcester and Commonwealth of Massachusetts, have invented and produced a new and original Design for a Water-Closet Seat, of which the following is a specification, reference being had to the accompanying drawings, forming part thereof.

10 Figure 1 is a plan or top view of a water-closet seat, showing my new design; and Fig. 2 is a sectional view taken on line 2 2, Fig. 1.

Similar reference letters and figures refer to different parts in both views.

15 As shown in the drawings, the leading or material feature of my design consists of a seat which is oval in its outline as viewed in plan view, as indicated by the line A, Fig. 1, and having a central opening B. The inner 20 portion of the seat next the opening B is depressed or dished from a point 1 near the front of the central opening B around the rear of the opening to a corresponding point

2 upon the opposite side of the opening. The dished portion consists of the part C of the 25 seat which is included between the central opening B and the line D, Fig. 1. The remaining upper portion E of the seat, which is inclosed between the lines A and D and also extends across the front of the opening B, 30 lies in the same horizontal plane. The edge of the seat is turned downwardly, forming a dependent flange F, substantially at right angles with the horizontal upper surface E of the seat, with the flange F and the body of the 35 seat of substantially the same thickness.

Having described my invention, what I claim as new, and desire to secure by Letters Patent, is—

The design for a water-closet seat as herein 40 shown and described.

EDWARD L. TAFT.
